CLAIM

The ornamental design for a pillow, as shown and described.

DESCRIPTION

FIG. 1 is a perspective view of the pillow showing my new design;

FIG. 2 is a top view thereof, with the bottom view being a mirror image;

FIG. 3 is a front view thereof;

FIG. 4 is a back view thereof;

FIG. 5 is right view thereof, with the left view being a mirror image; and,

FIG. 6 is an alternate right view thereof with the pillow flipped on its back side, with the alternate left view being a mirror image.

1 Claim, 4 Drawing Sheets
